UNITED STATES PATENT OFFICE

100,125

DESIGN FOR A TOOTH BRUSH

Velma E. Rominger, Salem, Oreg.

Application June 3, 1935, Serial No. 57,105

Term of patent 14 years

To all whom it may concern:

Be it known that I, Velma E. Rominger, a citizen of the United States residing at Salem, in the county of Marion and State of Oregon, have invented a new, original, and ornamental Design for Tooth Brushes, of which the following is a specification, reference being had to the accompanying drawing, forming part thereof.

Fig. 1 is a perspective view of a tooth brush showing my new design.

Fig. 2 is a detailed perspective view of the brush element removed from the barrel in Fig. 1; and

Fig. 3 is a cross-sectional view taken on the line 3—3 of Fig. 1, shown on slightly enlarged scale.

I claim:

The ornamental design for a tooth brush, as shown and described.

VELMA E. ROMINGER.
